UNITED STATES PATENT OFFICE.

MOSES G. FARMER, OF NEWPORT, RHODE ISLAND.

ELECTRIC LAMP.

SPECIFICATION forming part of Letters Patent No. 252,364, dated January 17, 1882.

Application filed May 26, 1881. (No model.)

To all whom it may concern:

Be it known that I, MOSES G. FARMER, of Newport, in the county of Newport and State of Rhode Island, have invented a new and useful Improvement in Electric Lamps, of which the following, taken in connection with the accompanying drawings, is a specification.

My invention relates to the construction of the lamp-stand, and the method of attaching the lamp thereto, and has for its object rendering the lamp capable of being readily removed from the stand for repairs without extinguishing or otherwise interfering with other lamps in the same circuit, and as readily replaced; and it consists, first, in a lamp-support made in two parts, arranged to be united or coupled together by a smooth stem or shank upon one part entering a correspondingly smooth socket formed for the purpose in the other part, one of said parts being permanently secured to the lamp-globe, and provided with wires leading from the opposite ends of the carbon within the globe, each terminating at its other end in a fixed annular metallic coupling-surface, insulated from the coupling-surface attached to the other wire, and the other part being provided with two sets of metallic spring or yielding couplings insulated from each other, and adapted to make a positive contact with the fixed coupling-surfaces on the other part of the lamp-support when the lamp is placed in position, said spring-couplings being connected respectively with the battery and with the main line directly or indirectly, as will be more fully described.

Figure 1 of the drawings is an elevation of an electric lamp with my improvements applied thereto. Fig. 2 is an inverted plan of the same. Fig. 3 is an inverted plan, illustrating the manner of applying the electro-magnet and armature. Fig. 4 is a vertical section on line xx on Fig. 2. Fig. 5 is a similar section on line yy on Fig. 2. Figs. 6 and 7 are horizontal sections on lines vv and zz respectively; and Fig. 8 is a partial vertical section corresponding to Fig. 4, drawn to an enlarged scale.

A is the glass globe containing the carbon a and the wires b and b' , each connected at one end to the carbon a , and extending downward therefrom through the neck of the inner por-

tion of the globe-shank, the glass of which is hermetically sealed around them, said wires being insulated from each other by the glass, which completely surrounds each of them. The 55 globe-shank A' is firmly secured in the socket B, made of wood, hard rubber, or other suitable insulating material, and having its lower portion reduced in diameter to form the shoulder c . The wire b extends through the material of the socket B in an oblique direction, and has its lower end soldered or otherwise made fast to the metallic ring d , surrounding and firmly secured to the periphery of the reduced portion of said socket, and the wire b' extends 60 downward through the material of the socket B in a vertical, or nearly vertical, direction, and is secured to the metallic pin e , set in the center of the lower end of the socket B, and projecting downward therefrom, as shown in 65 Figs. 4, 5, and 8.

C is the main stand or section of the lamp-support, provided with a broad base, C', in the under side of which is formed a circular recess, C², and provided with a cylindrical opening extending from said recess to the upper end of the stand C, the central portion of which opening is filled with the tubular plug D, driven tightly into said opening, and secured therein in such a position as to leave a recess at the 80 upper end of the stand C to receive the shank or stem of the socket B, as shown in Figs. 4, 5, and 8.

To the upper end of the tubular plug D are secured four metallic leaf-springs, f , f' , g , and g' , fitted to grooves formed in the exterior of said plug at about equal distances from each other, the springs f and f' being located directly opposite to each other, and extending upward nearly to the top of the stand C, while 90 the springs g and g' are also arranged opposite to each other, and about equidistant between the springs f and f' , and are bent inward over the top of the plug D and downward into the hole h made through the plug D, 95 in a position to press against the sides of the pin e when the socket B is placed in position in the stand C. The springs f and f' are so shaped and arranged as to insure contact between them and the metallic ring d when 100 the socket B is in position on the stand C, and said springs are connected by the wires i and

i' to the stem or shank of the screw-cup E, within the recess C², as shown in Figs. 2 and 4. The springs *g* and *g'* are in like manner connected by the wires *j* and *j'* to the metallic bracket *k*, secured to the under side of the stand C, within the recess C², as shown in Figs. 2 and 5.

F is a leaf-spring secured by one end to the wall of the recess C², and connected by the wire *l* to the lower end of the shank of the screw-cup G, the opposite end of said spring pressing hard against the pendent portion of the bracket *k*, as shown.

H is a switch-button, the shank of which passes through the base C' into the recess C², and has secured thereto the switch-plate or lever *m*, one end of which is held in contact with the pin *n* by the torsion of the spring *o*, coiled around the shank of the switch-button H. The shank of the button H has its bearing in a metallic socket, *p*, which is connected by means of the wire *q* with the resistance-coil I, which in turn is connected by the wire *r* with the shank of the screw-cup E, all as shown in Fig. 2.

The operation of my invention, as thus far described, is as follows: The screw-cups E and G being connected by suitable wires to a battery or other electric generator, with the switch-lever *m* in the position shown in Fig. 2, the current of electricity will pass from the screw-cup G through the wire *l*, spring F, bracket *k*, wires *j* and *j'*, springs *g* and *g'*, the pin *e*, and the wire *b'*, to the carbon *a*, and thence along the wire *b*, through the ring *d*, the springs *f* and *f'*, wires *i* and *i'*, to the screw-cup E, and thence to the battery or magneto-generator. The circuit being complete and all the parts in the positions shown, the passage of the current of electricity over the carbon *a* will cause a bright white light to be given off therefrom. If, now, the globe A, with the socket B, be removed from the stand C, the circuit will be broken and the light will be extinguished, and all other lights in the same line will also be extinguished; but if, before removing the globe and socket, the switch-button H is turned about its axis till the end of the switch-plate *m* forces the spring F away from contact with the bracket *k*, as indicated in dotted lines in Fig. 2, the current of electricity will pass from the battery to the screw-cup G, thence through the wire *l*, spring F, switch-plate *m*, socket *p*, wire *q*, resistance-coil I, and wire *r*, to the screw-cup E, and thence over the main line and back to the battery, and the circuit will thus remain unbroken, and all other lights in the same line will be unaffected by the removal of the lamp. This arrangement would work well in certain cases where all the lamps in the circuit were under the control of a single party, but does not provide for the accidental breakage, the burning out, or other inoperativeness of the carbon; and to meet this difficulty I secure to the stand C, within the recess C², the electro-magnet J, provided with the armature *s*, hinged

at one end to the bracket *s'*, and adapted to bear at its other end against the bracket *t*, against which it is pressed by the tension of the spring *s*². The bracket *s'* is connected by the wire *t'* to the bracket *k* and by the wire *t*² to the coils of the magnet J, the wire of which coils is connected at its other end to the wire *j*, before described as being connected to the bracket *k*. The parts being in the positions shown, and the circuit being completed, the current will pass from the battery to the screw-cup G, and thence through the wire *l*, spring F, bracket *k*, and wire *t'*, to the bracket *s'*, where the current is at first divided, a portion passing through the armature *s* and another portion through the wire *t*², to and through the coils of the magnet J, this latter portion being sufficient to magnetize the cores of said magnet to such a degree that they will attract the armature *s*, thus breaking its contact with the bracket *t*, when the whole of the current will pass through the coils of the magnet and thence through the wires *j* and *j'*, springs *g* and *g'*, the pin *e*, and the wire *b'*, to the carbon *a*, and thence along the wire *b*, through the ring *d*, the springs *f* and *f'*, wires *i* and *i'*, to the screw-cup E, and thence to the starting-point; but if the carbon *a* should become broken, or the globe A and socket B are removed, so as to break the circuit in its passage through the lamp, the armature *s* would be immediately drawn away from the magnet by the spring *s*² till its movable end is brought in contact with the bracket *t*, when the circuit is again completed, with the injured lamp cut out, and all the other lamps in the circuit will continue to give off light as though nothing had happened, the current passing from the bracket *s'*, through the armature *s*, to the bracket *t*, and thence over the wire *u*, to and through the resistance-coil I, through the wire *r*, to the screw-cup E, and thence to the starting-point.

Whenever it is desired to extinguish the light of any lamp in the circuit without removing the globe from its stand, and without extinguishing the lights of any other lamps in the circuit, it is only necessary to turn the switch-button H till the switch-plate *m* forces the spring F away from the bracket *k*, as indicated in dotted lines, when the current will pass from the screw-cup G, through wire *l*, spring F, switch *m* H, socket *p*, wire *q*, resistance-coil I, and the wire *r*, to the screw-cup E, as before described.

The advantages of using my improved construction of electric lamps are, that in case of accident to any lamp in a circuit containing more than one, the circuit is maintained unbroken, and the other lamps in the circuit are unaffected by said accident; also, that the injured lamp can be removed and a perfect one put in its place in a very few seconds, even in the dark, without the necessity of calling in a skilled workman to make the connections; and also that any one of a series of lamps in the same circuit can be extinguished and relighted

at the pleasure of the party controlling the same, without interfering in the least with any other lamp in the circuit.

What I claim as new, and desire to secure by Letters Patent of the United States, is—

The globe A, mounted in the socket B, in combination with the carbon a contained in said globe, the wires b and b', connected at one end to said carbon, the metallic ring d, connected to the other end of the wire b, the pin e, connected to the wire b', the stand C, provided

with one or more springs, ff', and one or more springs, gg', and the wires i i' and jj', all arranged and adapted to operate substantially as and for the purposes described.

Executed at Newport, Rhode Island, this 2d day of April, A. D. 1881.

MOSES GERRISH FARMER.
